DESIGN FOR AN END STANDARD FOR THEATER CHAIRS

Leo Jiranek, New York, N. Y., assignor to Heywood-Wakefield Company, Gardner, Mass., a corporation of Massachusetts

Application July 8, 1940, Serial No. 93,560

Term of patent 7 years

To all whom it may concern:

Be it known that I, Leo Jiranek, a citizen of the United States and a resident of New York, county of New York, and State of New York, have invented a new, original, and ornamental Design for an End Standard for Theater Chairs, of which the following is a specification, reference being had to the accompanying drawing, forming a part thereof. In said drawing Fig. 1 is a view in side elevation of an end standard for theater chairs showing my new design. Fig. 2 is a view

in front elevation thereof. Fig. 3 is a view in elevation of the standard when viewed from the bottom end thereof. Figs. 4 and 5 are horizontal sectional views through parts of the standard as taken on the lines 4—4 and 5—5 respectively of Fig. 1.

I claim:

The ornamental design for an end standard for theater chairs, substantially as shown.

LEO JIRANEK.
